L. TOWL

MEANS FOR HOLDING ABRASIVE, POLISHING, OR LIKE MATERIAL

Filed Nov. 20, 1922

INVENTOR:

Leslie Towl

By *Milans Milans*
Attorneys

UNITED STATES PATENT OFFICE.

LESLIE TOWL, OF LONDON, ENGLAND.

MEANS FOR HOLDING ABRASIVE, POLISHING, OR LIKE MATERIAL.

Application filed November 20, 1922. Serial No. 602,128.

To all whom it may concern:

Be it known that I, LESLIE Towl, a subject of the King of Great Britain, residing at No. 155 Earlham Grove, Forest Gate, 5 London, E., England, have invented a Means for Holding Abrasive, Polishing, or like Material, of which the following is the specification.

The object of this invention is to provide 10 better means than have hitherto been devised for securely holding abrasive or polishing or like material upon a handle or bar or the like means for operating the said material.

15 And in order that my invention may be completely understood reference should be made to the accompanying sheet of drawings which illustrates the preferred form of construction.

20 Fig. 1 is an elevation or edge view of the new tool.

Fig. 2 is a plan of same.

Fig. 3 is a view with the handle detached and with the abrasive material loose.

25 Fig. 4 shows the handle and taper thereon.

Fig. 5 is a section showing a casing having a concave face for the abrasive.

Fig. 6 shows a similar section with a convex face.

30 Fig. 7 shows a knob on the adjustable L-piece to be gripped by the left hand in operating the implement.

The casing A is hollow for the greater part of its length and is also of tapered 35 form on its interior. The front face of the casing has a true or plane surface upon which is adapted to be stretched or securely held the abrasive material B such as emery cloth. One end of the abrasive material is

40 folded inside the casing and is clamped in position by the handle C which may be made of wood or any other suitable material and which is formed with a corresponding taper to that of the interior of the casing. The handle removed from the casing is shown at Fig. 4 which figure also shows a suitable degree of taper C' for the handle.

45 When the abrasive material is folded within the casing the taper of the handle is pushed into the casing until it tightly fits therein, and thus grips the end of the abrasive material, the position of which is indicated in Fig. 3, tightly between the tapered handle and the casing. The other end 50 of the strip of abrasive material is secured

to the casing by means of the projecting stud D which is rigidly secured in the back of the casing. The end of the strip is clamped between the angular metal plate E and the plate F by means of the screws E' 60 E². The plate F is formed with a longitudinal slot F' which fits over the stud D. The base of the stud has a rectangular head D' which head is a sliding fit in the slot F' and prevents any possibility of the plate F 65 turning upon the stud D. A nut D² with a milled head has a thread fitting the stud D and has a washer D³ fitted between the nut and the plate F.

When the abrasive material is secured by 70 the tapered handle C as before described, and has been clamped between the L-plate E and the plate F by the said screws, the strip of abrasive material is pulled tight over the end of the casing by gripping the plate E 75 and the nut D² with the washer is then screwed home upon the plate F to hold the plates E and F in position upon the back of the casing A, thus securing the abrasive material B in its stretched condition upon 80 the face of the implement ready for use.

Referring to Fig. 3, this shows the abrasive material loose in position on the casing ready for the tapered handle shown in Fig. 4 to be fitted therein and for the abrasive 85 material to be tightened at the other end of the casing on the nut D as before described.

Fig. 5 shows a section of a casing A having abrasive material B secured on a concave face in order that the abrasive material may be used on a rounded or curved 90 surface of work.

Fig. 6 shows a section having a casing with a convex face adapted to be used upon a concave surface of metal.

95 While the casing A with the strip of abrasive or polishing material secured thereto, may be held by one hand by the handle C, provision is also made for gripping the holder at the other end thereof by the other hand of the user, and for this purpose a knob or the like may be provided at the outer or projecting end of one of the clamping plates that forms part of the clamping and securing means for one end of the abrasive or polishing strip at one end of the holder or casing, as illustrated in the modified construction Figure 7 of the drawings in which one of the clamping members designated E is provided with a knob or handle 100 105 110

part E³, said knob or handle part E³ being adapted to be gripped and receive the pressure of the left hand in using the implement.

By the special construction and arrangement of parts hereinbefore described, means of a simple efficient nature is afforded whereby the flexible strip of polishing or abrasive material can be securely held on the face of the holder or casing. The strip securing means at one end of the holder or casing is readily adjustable, said means providing for adjustably tightening as well as securing at one end said strip upon the face of the casing or holder.

15. What I do claim as my invention and desire to secure by Letters Patent is:—

1. A device of the class described, comprising a flexible abrasive or polishing strip, a holder for said strip provided with a tubular end portion, a handle member having a part adapted to fit within the tubular end portion of the holder and serving to clamp one end of the flexible abrasive or polishing strip to the holder within the tubular end portion thereof, and securing means for the other end of the flexible abrasive or polishing strip on the holder.

2. A device of the class described, comprising a flexible abrasive or polishing strip, a holder for said strip provided with an inwardly tapering tubular end portion, a handle member having a wedge shaped part adapted to fit within the tapering tubular end portion of the holder and serving to clamp one end of the flexible abrasive or polishing strip to the holder within the tubular end portion thereof, and means on the other end portion of the holder for securing the other end of the flexible abrasive or polishing strip thereto.

3. A device of the class described comprising a flexible abrasive or polishing strip, a holder for said strip provided with a tubular end portion, a handle member having a part adapted to fit within the tubular end portion of the holder and serve to clamp one end of the flexible abrasive or polishing strip to the holder within the tubular end portion thereof, and means for adjustably securing the other end of the flexible abrasive or polishing strip to the holder, said last mentioned means comprising a stud on the rear face of the holder at the other end portion thereof, said stud having a threaded portion, a pair of plates, means for secur-

ing said plates together with the end of the flexible abrasive or polishing strip clamped therebetween, one of said plates being provided with a slot to engage the said stud, and a nut to engage the threaded portion 60 of the stud and clamp said plate to the holder.

4. A device of the class described, comprising a flexible abrasive or polishing strip, a holder for said strip provided with a tubular end portion, a handle member having a wedge shaped part adapted to fit within the tubular end portion of the holder and serving to clamp one end of the flexible abrasive or polishing strip to the holder within 70 the tubular end portion thereof, and means on the other end portion of the holder for securing the other end of the flexible abrasive or polishing strip thereto, said last mentioned means carrying a laterally extending handle part.

5. A device of the class described, comprising a flexible abrasive or polishing strip, a holder for said strip provided with a tubular end portion, a handle member having a wedge shaped part adapted to fit within the tubular end portion of the holder and serve to clamp one end of the flexible abrasive or polishing strip to the holder within the tubular end portion thereof, and means for securing the other end of the flexible abrasive or polishing strip to the holder, said last mentioned means including a pair of plates, means for securing said plates together with the end of the flexible abrasive or polishing strip clamped therebetween and for securing one of said plates to the holder, and a handle part on one of said plates.

6. A device of the class described, comprising a flexible abrasive or polishing strip, a holder for said strip, the holder being tubular for the greater portion of its length, said tubular portion of the holder extending from one end thereof and having inwardly tapering inner walls, a handle member having an extension portion of a length substantially the length of the tubular portion of the holder and formed tapering to fit within the tubular portion of the holder and clamp one end of the flexible abrasive or polishing strip to the holder within the tubular portion thereof, and securing means on the holder for the other end of the flexible abrasive or polishing strip.

LESLIE TOWL.
